Primary Examiner — Austin Murphy

(57) **CLAIM**

The ornamental design for a sound collection device, as shown and described.

DESCRIPTION

FIG. 1 is a front, top and right side perspective view of a sound collection device showing our new design; FIG. 2 is a rear, bottom and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a rear, bottom and right side perspective view showing the sound collection device in a use state.

The broken lines in the drawings illustrate portions of the sound collection device which form no part of the claimed design. A portion of the sound collection device is broken away to indicate that no particular length is claimed. The oblique shade lines in the drawings represent reflective surfaces.
